3 Sheets-Sheet 3

<img alt="A detailed technical cross-sectional diagram of a mechanical device, likely a pump or compressor, labeled FIG. 3. The diagram shows various components including a pump body (118), a piston (113), a connecting rod (120), a crankshaft (119), and a flywheel (125). A control system is integrated with the mechanical parts, featuring a solenoid (101), a pressure gauge (66), and a series of valves and piping. Numerous reference numerals are used to identify specific parts and assembly points, such as 73, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 661, 662, 663, 664, 665, 666, 667, 668, 669, 670, 671, 672, 673, 674, 675, 676, 677, 678, 679, 680, 681, 682, 683, 684, 685, 686, 687, 688, 689, 690, 691, 692, 693, 694, 695, 696, 697, 698, 699, 700, 701, 702, 703, 704, 705, 706, 707, 708, 709, 710, 711, 712, 713, 714, 715, 716, 717, 718, 719, 720, 721, 722, 723, 724, 725, 726, 727, 728, 729, 730, 731, 732, 733, 734, 735, 736, 737, 738, 739, 731, 732, 733, 734, 735, 736, 737, 738, 739, 740, 741, 742, 743, 744, 745, 746, 747, 748, 749, 741, 742, 743, 744, 745, 746, 747, 748, 749, 750, 751, 752, 753, 754, 755, 756, 757, 758, 759, 751, 752, 753, 754, 755, 756, 757, 758, 759, 760, 761, 762, 763, 764, 765, 766, 767, 768, 769, 761, 762, 763, 764, 765, 766, 767, 768, 769, 770, 771, 772, 773, 774, 775, 776, 777, 778, 779, 771, 772, 773, 774, 775, 776, 777, 778, 779, 780, 781, 782, 783, 784, 785, 786, 787, 788, 789, 781, 782, 783, 784, 785, 786, 787, 788, 789, 790, 791, 792, 793, 794, 795, 796, 797, 798, 799, 791, 792, 793, 794, 795, 796, 797, 798, 799, 800, 801, 802, 803, 804, 805, 806, 807, 808, 809, 801, 802, 803, 804, 805, 806, 807, 808, 809, 810, 811, 812, 813, 814, 815, 816, 817, 818, 819, 811, 812, 813, 814, 815, 816, 817, 818, 819, 820, 821, 822, 823, 824, 825, 826, 827, 828, 829, 821, 822, 823, 824, 825, 826, 827, 828, 829, 830, 831, 832, 833, 834, 835, 836, 837, 838, 839, 831, 832, 833, 834, 835, 836, 837, 838, 839, 840, 841, 842, 843, 844, 845, 846, 847, 848, 849, 841, 842, 843, 844, 845, 846, 847, 848, 849, 850, 851, 852, 853, 854, 855, 856, 857, 858, 859, 851, 852, 853, 854, 855, 856, 857, 858, 859, 860, 861, 862, 863, 864, 865, 866, 867, 868, 869, 861, 862, 863, 864, 865, 866, 867, 868, 869, 870, 871, 872, 873, 874, 875, 876, 877, 878, 879, 871, 872, 873, 874, 875, 876, 877, 878, 879, 880, 881, 882, 883, 884, 885, 886, 887, 888, 889, 881, 882, 883, 884, 885, 886, 887, 888, 889, 890, 891, 892, 893, 894, 895, 896, 897, 898, 899, 891, 892, 893, 894, 895, 896, 897, 898, 899, 900, 901, 902, 903, 904, 905, 906, 907, 908, 909, 901, 902, 903, 904, 905, 906, 907, 908, 909, 910, 911, 912, 913, 914, 915, 916, 917, 918, 919, 911, 912, 913, 914, 915, 916, 917, 918, 919, 920, 921, 922, 923, 924, 925, 926, 927, 928, 929, 921, 922, 923, 924, 925, 926, 927, 928, 929, 930, 931, 932, 933, 934, 935, 936, 937, 938, 939, 931, 932, 933, 934, 935, 936, 937, 938, 939, 940, 941, 942, 943, 944, 945, 946, 947, 948, 949, 941, 942, 943, 944, 945, 946, 947, 948, 949, 950, 951, 952, 953, 954, 955, 956, 957, 958, 959, 951, 952, 953, 954, 955, 956, 957, 958, 959, 960, 961, 962, 963, 964, 965, 966, 967, 968, 969, 961, 962, 963, 964, 965, 966, 967, 968, 969, 970, 971, 972, 973, 974, 975, 976, 977, 978, 979, 971, 972, 973, 974, 975, 976, 977, 978, 979, 980, 981, 982, 983, 984, 985, 986, 987, 988, 989, 981, 982, 983, 984, 985, 986, 987, 988, 989, 990, 991, 992, 993, 994, 995, 996, 997, 998, 999, 991, 992, 993, 994, 995, 996, 997, 998, 999, 1000, 1001, 1002, 1003, 1004, 1005, 1006, 1007, 1008, 1009, 1001, 1002, 1003, 1004, 1005, 1006, 1007, 1008, 1009, 1010, 1011, 1012, 1013, 1014, 1015, 1016, 1017, 1018, 1019, 1011, 1012, 1013, 1014, 1015, 1016, 1017, 1018, 1019, 1020, 1021, 1022, 1023, 1024, 1025, 1026, 1027, 1028, 1029, 1021, 1022, 1023, 1024, 1025, 1026, 1027, 1028, 1029, 1030, 1031, 1032, 1033, 1034, 1035, 1036, 1037, 1038, 1039, 1031, 1032, 1033, 1034, 1035, 1036, 1037, 1038, 1039, 1040, 1041, 1042, 1043, 1044, 1045, 1046, 1047, 1048, 1049, 1041, 1042, 1043, 1044, 1045, 1046, 1047, 1048, 1049, 1050, 1051, 1052, 1053, 1054, 1055, 1056, 1057, 1058, 1059, 1051, 1052, 1053, 1054, 1055, 1056, 1057, 1058, 1059, 1060, 1061, 1062, 1063, 1064, 1065, 1066, 1067, 1068, 1069, 1061, 1062, 1063, 1064, 1065, 1066, 1067, 1068, 1069, 1070, 1071, 1072, 1073, 1074, 1075, 1076, 1077, 1078, 1079, 1071, 1072, 1073, 1074, 1075, 1076, 1077, 1078, 1079, 1080, 1081, 1082, 1083, 1084, 1085, 1086, 1087, 1088, 1089, 1081, 1082, 1083, 1084, 1085, 1086, 1087, 1088, 1089, 1090, 1091, 1092, 1093, 1094, 1095, 1096, 1097, 1098, 1099, 1091, 1092, 1093, 1094, 1095, 1096, 1097, 1098, 1099, 1100, 1101, 1102, 1103, 1104, 1105, 1106, 1107, 1108, 1109, 1101, 1102, 1103, 1104, 1105, 1106, 1107, 1108, 1109, 1110, 1111, 1112, 1113, 1114, 1115, 1116, 1117, 1118, 1119, 1111, 1112, 1113, 1114, 1115, 1116, 1117, 1118, 1119, 1120, 1121, 1122, 1123, 1124, 1125, 1126, 1127, 1128, 1129, 1121, 1122, 1123, 1124, 1125, 1126, 1127, 1128, 1129, 1130, 1131, 1132, 1133, 1134, 1135, 1136, 1137, 1138, 1139, 1131, 1132, 1133, 1134, 1135, 1136, 1137, 1138, 1139, 1140, 1141, 1142, 1143, 1144, 1145, 1146, 1147, 1148, 1149, 1141, 1142, 1143, 1144, 1145, 1146, 1147, 1148, 1149, 1150, 1151, 1152, 1153, 1154, 1155, 1156, 1157, 1158, 1159, 1151, 1152, 1153, 1154, 1155, 1156, 1157, 1158, 1159, 1160, 1161, 1162, 1163, 1164, 1165, 1166, 1167, 1168, 1169, 1161, 1162, 1163, 1164, 1165, 1166, 1167, 1168, 1169, 1170, 1171, 1172, 1173, 1174, 1175, 1176, 1177, 1178, 1179, 1171, 1172, 1173, 1174, 1175, 1176, 1177, 1178, 1179, 1180, 1181, 1182, 1183, 1184, 1185, 1186, 1187, 1188, 1189, 1181, 1182, 1183, 1184, 1185, 1186, 1187, 1188, 1189, 1190, 1191, 1192, 1193, 1194, 1195, 1196, 1197, 1198, 1199, 1191, 1192, 1193, 1194, 1195, 1196, 1197, 1198, 1199, 1200, 1201, 1202, 1203, 1204, 1205, 1206, 1207, 1208, 1209, 1201, 1202, 1203, 1204, 1205, 1206, 1207, 1208, 1209, 1210, 1211, 1212, 1213, 1214, 1215, 1216, 1217, 1218, 1219, 1211, 1212, 1213, 1214, 1215, 1216, 1217, 1218, 1219, 1220, 1221, 1222, 1223, 1224, 1225, 1226, 1227, 1228, 1229, 1221, 1222, 1223, 1224, 1225, 1226, 1227, 1228, 1229, 1230, 1231, 1232, 1233, 1234, 1235, 1236, 1237, 1238, 1239, 1231, 1232, 1233, 1234, 1235, 1236, 1237, 1238, 1239, 1240, 1241, 1242, 1243, 1244, 1245, 1246, 1247, 1248, 1249, 1241, 1242, 1243, 1244, 1245, 1246, 1247, 1248, 1249, 1250, 1251, 1252, 1253, 1254, 1255, 1256, 1257, 1258, 1259, 1251, 1252, 1253, 1254, 1255, 1256, 1257, 1258, 1259, 1260, 1261, 1262, 1263, 1264, 1265, 1266, 1267, 1268, 1269, 1261, 1262, 1263, 1264, 1265, 1266, 1267, 1268, 1269, 1270, 1271, 1272, 1273, 1274, 1275, 1276, 1277, 1278, 1279, 1271, 1272, 1273, 1274, 1275, 1276, 1277, 1278, 1279, 1280, 1281, 1282, 1283, 1284, 1285, 1286, 1287, 1288, 1289, 1281, 1282, 1283, 1284, 1285, 1286, 1287, 1288, 1289, 1290, 1291, 1292, 1293, 1294, 1295, 1296, 1297, 1298, 1299, 1291, 1292, 1293, 1294, 1295, 1296, 1297, 1298, 1299, 1300, 1301, 1302, 1303, 1304, 1305, 1306, 1307, 1308, 1309, 1301, 1302, 1303, 1304, 1305, 1306, 1307, 1308, 1309, 1310, 1311, 1312, 1313, 1314, 1315, 1316, 1317, 1318, 1319, 1311, 1312, 1313, 1314, 1315, 1316, 1317, 1318, 1319, 1320, 1321, 1322, 1323, 1324, 1325, 1326, 1327, 1328, 1329, 1321, 1322, 1323, 1324, 1325, 1326, 1327, 1328, 1329, 1330, 1331, 1332, 1333, 1334, 1335, 1336, 1337, 1338, 1339, 1331, 1332, 1333, 1334, 1335, 1336, 1337, 1338, 1339, 1340, 1341, 1342, 1343, 1344, 1345, 1346, 1347, 1348, 1349, 1341, 1342, 1343, 1344, 1345, 1346, 1347, 1348, 1349, 1350, 1351, 1352, 1353, 1354, 1355, 1356, 1357, 1358, 1359, 1351, 1352, 1353, 1354, 1355, 1356, 1357, 1358, 1359, 1360, 1361, 1362, 1363, 1364, 1365, 1366, 1367, 1368, 1369, 1361, 1362, 1363, 1364, 1365, 1366, 1367, 1368, 1369, 1370, 1371, 1372, 1373, 1374, 1375, 1376, 1377, 1378, 1379, 1371, 1372, 1373, 1374, 1375, 1376, 1377, 1378, 1379, 1380, 1381, 1382, 1383, 1384, 1385, 1386, 1387, 1388, 1389, 1381, 1382, 1383, 1384, 1385, 1386, 1387, 1388, 1389, 1390, 1391, 1392, 1393, 1394, 1395, 1396, 1397, 1398, 1399, 1391, 1392, 1393, 1394, 1395, 1396, 1397, 1398, 1399, 1400, 1401, 1402, 1403, 1404, 1405, 1406, 1407, 1408, 1409, 1401, 1402, 1403, 1404, 1405, 1406, 1407, 1408, 1409, 1410, 1411, 1412, 1413, 1414, 1415, 1416, 1417, 1418, 1419, 1411, 1412, 1413, 1414, 1415, 1416, 1417, 1418, 1419, 1420, 1421, 1422, 1423, 1424, 1425, 1426, 1427, 1428, 1429, 1421, 1422, 1423, 1424, 1425, 1426, 1427, 1428, 1429, 1430, 1431, 1432, 1433, 1434, 1435, 1436, 1437, 1438, 1439, 1431, 1432, 1433, 1434, 1435, 1436, 1437, 1438, 1439, 1440, 1441, 1442, 1443, 1444, 1445, 1446, 1447, 1448, 1449, 1441, 1442, 1443, 1444, 1445, 1446, 1447, 1448, 1449, 1450, 1451, 1452, 1453, 1454, 1455, 1456, 1457, 1458, 1459, 1451, 1452, 1453, 1454, 1455, 1456, 1457, 1458, 1459, 1460, 1461, 1462, 1463, 1464, 1465, 1466, 1467, 1468, 1469, 1461, 1462, 1463, 1464, 1465, 1466, 1467, 1468, 1469, 1470, 1471, 1472, 1473, 1474, 1475, 1476, 1477, 1478, 1479, 1471, 1472, 1473, 1474, 1475, 1476, 1477, 1478, 1479, 1480, 1481, 1482, 1483, 1484, 1485, 1486, 1487, 1488, 1489, 1481, 1482, 1483, 1484, 1485, 1486, 1487, 1488, 1489, 1490, 1491, 1492, 1493, 1494, 1495, 1496, 1497, 1498, 1499, 1491, 1492, 1493, 1494, 1495, 1496, 1497, 1498, 1499, 1500, 1501, 1502, 1503, 1504, 1505, 1506, 1507, 1508, 1509, 1501, 1502, 1503, 1504, 1505, 1506, 1507, 1508, 1509, 1510, 1511, 1512, 1513, 1514, 1515, 1516, 1517, 1518, 1519, 1511, 1512, 1513, 1514, 1515, 1516, 1517, 1518, 1519, 1520, 1521, 1522, 1523, 1524, 1525, 1526, 1527, 1528, 1529, 1521, 1522, 1523, 1524, 1525, 1526, 1527, 1528, 1529, 1530, 1531, 1532, 1533, 1534, 1535, 1536, 1537, 1538, 1539, 1531, 1532, 1533, 1534, 1535, 1536, 1537, 1538, 1539, 1540, 1541, 1542, 1543, 1544, 1545, 1546, 1547, 1548, 1549, 1541, 1542, 1543, 1544, 1545, 1546, 1547, 1548, 1549, 1550, 1551, 1552, 1553, 1554, 1555, 1556, 1557, 1558, 1559, 1551, 1552, 1553, 1554, 1555, 1556, 1557, 1558, 1559, 1560, 1561, 1562, 1563, 1564, 1565, 1566, 1567, 1568, 1569, 1561, 1562, 1563, 1564, 1565, 1566, 15

CONTROL FOR HEATING SYSTEMS

Willet E. Stark, East Cleveland, Ohio, assignor,
by mesne assignments, to The Bryant Heater
Company, Cleveland, Ohio, a corporation of
Ohio

Application October 13, 1931, Serial No. 568,583

1 Claim. (Cl. 237—2)

This invention relates to improvements in controls for heating systems, that is to say automatic means for so operating a heating system as to maintain the temperature of the premises constantly at a desired point, or within a short range of variation. The present invention is designed primarily for use in connection with liquid or gaseous fuel, but by means of changes within the skill of the experienced worker in the art it may 10 be adapted in some of its aspects, at least, to use with solid fuels as well.

One of the objects of the invention is the provision of an automatic control for warm air heating systems, wherein not only the heat supplied 15 to the circulating air is regulated in accordance with a demand for heat, but also one wherein the circulation of air may be started and stopped or varied in volume to conform with the requirements.

Another object is the employment in connection 20 with two different heating systems, using a common source of heat, of provision for controlling the operation of the source of heat to satisfy with comparative exactness the demands placed upon 25 both systems, regardless of how different they may be.

Other objects and features of novelty will appear as I proceed with the description of that embodiment of the invention which, for the purposes 30 of the present application, I have illustrated in the accompanying drawings, in which

Figure 1 is an elevational view showing more or less diagrammatically a combined warm air and direct radiation heating system embodying the 35 invention.

Fig. 2 is an elevational view of the same, taken at right angles to Fig. 1.

Fig. 3 is a wiring diagram, showing electrical 40 circuits which may be employed in connection with the invention.

Fig. 4 is an elevational view, partly in vertical section, and on a larger scale, showing a fuel valve and associated parts which may be employed in connection with the invention.

Fig. 5 is a detail of a valve operator which may 45 be employed in connection with the invention.

Warm air heating systems, without auxiliaries, are sometimes unsatisfactory, particularly where 50 certain portions of the premises are comparatively distant from the furnace. In order to make the warm air system available in such cases for those portions of the premises which are within proper range of such a system, as well as to remove any possibility of the products of combustion getting into the air stream, I devised the

combination warm air and direct radiation system disclosed in my copending application Serial No. 542,370, filed June 5, 1931, where a fluid radiator is located in the air conductor for supplying heat to the air stream, and where other radiators 5 are located in the remote portions of the premises for heating the latter by direct radiation, all of the radiators being served by a single boiler. The present invention has to do with the provision of an automatic control for such a system, although 10 incidentally including features which are applicable to warm air systems generally.

In the drawing the boiler of the system is indicated at 10, and the air heater, comprising part of the conductor for the air stream, is shown at 15 11. A warm air conduit 12 is shown leading to a section 13 of the premises to be heated. It is to be understood that this section 13 may comprise a number of rooms, and that the conduit 12 may have any number of branches required to 20 supply warm air to such rooms. The return or air inlet conduit for the heater is indicated at 14, and is supplied with a damper 15 pivoted at 16 and adapted to be swung by means of a crank arm 17 from the fully closed position illustrated 25 in Fig. 2 to a fully open position at right angles thereto, or any intermediate position. Another section 18 of the premises, which may consist of one or a plurality of rooms, is arranged to be heated by direct radiation from one or more 30 radiators 19 which are directly connected with the boiler 10 through steam pipes 20, 21 and 22, the water of condensation from these pipes flowing back to the boiler through pipes 23 and 24. The condensation water from radiators 19 returns 35 to the boiler through pipes 25, 26 and 27.

Where gaseous fuel is employed, it may be fed to the burner (not shown) in the casing of boiler 10 through a pipe 28, in which is mounted a valve 29 of known form comprising a pressure 40 operated diaphragm. Preferably this valve 29 is one of the type which may be opened and closed by variations in pressure exerted upon the diaphragm, so that it may be adapted to be closed 45 when the pressure of steam in the boiler becomes excessive, as well as when thermostatic mechanism calls for an interruption of the heating operation, and so that it may also be opened to various degrees, dependent upon the degree of 50 steam pressure in the boiler.

Although valves of this general character are well known in the art, and one of the particular design herein disclosed is illustrated in my co-pending application Serial No. 396,279, filed 55

September 30, 1929, that shown herein will now be briefly described.

The valve housing comprises upper and lower parts 30 and 31, separated by a flexible diaphragm 32, to which is centrally attached a disc valve 34 which is adapted to engage a circular valve seat 35. A rod 33 vertically movable in a guide bracket 36 is adapted to bear upon the upper side of diaphragm 32, and carries on its upper end a second diaphragm 37 which is mounted at its periphery in a steam dome or chamber 38. A lever 39, pivoted at 40 in the bracket 36, extends through a slot in the rod 33, and at its free end engages by means of an adjustable fitting a coil spring 41, the opposite end of which may be suitably connected with the upper part 30 of the valve housing. Spring 41, working through lever 39, may be adjusted to balance the normal steam pressure exerted upon the upper side of diaphragm 37, so that steam pressure will completely close the valve only when the pressure is excessive. The chamber above diaphragm 37 is connected with the steam chest of the boiler through pipe 42.

Connected with the valve chamber beneath disc 34 there is a gas pipe 47, while another gas pipe 48 is connected with the chamber 49 above the diaphragm 32. When gas is permitted to flow from pipe 28 through pipes 47 and 48 into the chamber 49, pressure builds up in the latter chamber and depresses diaphragm 32 to close the valve. There is also a small relief connection (not shown) adapted to dissipate this pressure and permit the valve to open when the connection between pipes 47 and 48 is interrupted.

The connection between pipes 47 and 48 is made at times by way of a pipe 50 wherein there is a valve casing 51, see Fig. 3, in which there is a valve seat for the reception of a mushroom valve 52 on the lower extremity of a rod 53 of insulating material, which carries an armature 54 that is arranged to move up and down within a solenoid 55, having upper and lower coils 56 and 57 respectively. When the upper coil is energized the armature 54 is raised and the valve 52 lifted off its seat, whereupon gas pressure builds up in chamber 49 and closes valve 29. On the other hand, when coil 57 is energized, armature 54 is drawn downwardly, closing valve 52 and enabling the pressure above diaphragm 32 to be dissipated, whereupon valve 29 opens.

Referring again to Figs. 1 and 2, 58 is a steam pipe leading from the boiler to a radiator 59 mounted in the upper end of the casing of the air heater 11. The water condensed in radiator 59 is returned by means of pipes 60 and 61 to the boiler. This radiator is preferably furnished with sheet metal fins so as to provide a large amount of radiating surface and rapid condensation of the steam flowing therethrough whenever there is a current of air thereover. Preferably I provide a forced draft of air through the heater 11 by means of a fan or blower 62 mounted upon a shaft 63 which carries a pulley 64 outside of the casing driven by a belt 65 from an electric motor 66.

The crank arm 17 for the damper 15 is connected by means of a link 67 to the outer end of a lever 68 which protrudes from a box 69 containing mechanism for the movement of the lever up and down, and also an electric switch actuated by the lever. 70 is a cable containing electric conductors leading from a thermostat 71 in section 13 of the premises to box 69. From this

same box electric cables 72 and 73 lead to solenoid 55 and motor 66 respectively.

In the section 18 of the premises there is a second thermostat 74, from which a cable 75 leads to a switch and motor box 76 arranged to control a valve 9 in the steam pipe 20. From the box 76 a further cable 77 extends downwardly to solenoid 55.

Referring now to Fig. 3, in which the control mechanism and electric circuits are shown diagrammatically, 78 and 79 are high voltage conductors to which is connected the primary coil 80 of a step-down transformer. To the secondary coil 81 thereof are connected the various pieces of electrical apparatus which effect the automatic control of the two systems, although the motors for driving the blower and operating the valve 9 take high voltage current direct from the line 78, 79.

Within the box 69 there is mounted what is known in the art as a heat motor. As herein shown it comprises two bimetallic strips 82 and 83, which are secured at one end, as indicated at 82' and 83', to a suitable base, the opposite ends of the strips being hook shaped. Surrounding these strips are heating coils 84 and 85, the inner ends of which are electrically connected to the strips, while the remaining parts of the coils are electrically insulated therefrom. A yoke member 86 is mounted upon the hooked ends of the strips 82, 83 and carries a contact 87 which is adapted to engage at times with an adjustable contact 88 supported upon the lower end of a link 89 which is secured at its upper end to an arm 90 that is mounted upon a metal bellows 91 and engages the underside of lever 68, the latter being pivoted to a fixed support at 92. Within the box 69 there is also fixedly mounted a capsule 93 containing a volatile liquid. A second lever 94 is also pivoted at 95 to a suitable support in the box 69, and is connected at its outer end by a link 96 with lever 68 so as to move with that lever. The lever 94 serves as a movable support for two mercury tube switches 97 and 98 containing globules of mercury 99 and 100.

The thermostat 71 comprises a potentiometer coil 101 over which runs the end of a pointer 102 which has thermostatic properties, being made for instance as a bimetallic strip, so that as it moves over the coil 101 in response to temperature changes the resistances of the portions of coil 101 on either side thereof vary. The cable 70 extending from the thermostat 71 to the box 69 contains three conductors 70a, 70b and 70c connected as shown. 70c leads to heating coil 84 and 70a leads to heating coil 85. Current to heat both coils flows from the secondary coil 81 of the step-down transformer through a conductor 103 to strip 82, and by way of a connecting conductor 104 to strip 83. Thence it flows through the coils 84 and 85, and back through conductors 70c and 70a to the outer ends of potentiometer coil 101, flowing inwardly along the coil of the potentiometer to the pointer 102 and down through conductor 70b, returning through conductors 105 and 106 to coil 81. The position of pointer 102 will determine the resistance in the circuits for the two heating coils, and hence will vary the heating effects upon the bimetallic strips 82 and 83, which in turn will cause contact 87 to move either toward the right or the left for each change in temperature of the atmosphere surrounding thermostat 71. This thermostat having been set for any desired room temperature, any variation therefrom will thus

cause contact 87 to take a different position to the right or the left of its normal position. Assuming that it moves to the left, and engages contact 88, a circuit will then be set up from coil 81 to conductors 103 and 104, to conductor 107, yoke 86, contacts 87 and 88 and through a heating coil 108 surrounding capsule 93, and back through a conductor 109 and conductor 106 to coil 81. The liquid in capsule 81 will thereby be 5 volatilized, and bellows 91 will be expanded, exerting a lifting effort upon lever 68. At the same time the contact 88 is raised. As soon as the circuit through heating coil 108 is broken the pressure within bellows 91 rapidly decreases, 10 tending to lower the lever and the contact 88. The making and breaking of the circuit in this manner recurs rapidly, so that the contact 88 floats just at the point of engagement with contact 87, and hence for any given position of contact 87 there is a definite position of lever 68.

When the thermostat 74 is not calling for heat, the control apparatus will stand as illustrated in Fig. 3 except that pointer 102 will be at one extremity of coil 101. Under such conditions there will be no current through motor 66, which is connected with line wire 79 by conductor 73a and with mercury tube 97 by a conductor 73b which runs into the higher end of the tube. Another conductor 110 terminates in the tube 30 near the end of conductor 73b.

The mercury tube 98 constitutes a double switch for the control of the two coils of solenoid 55. It has connection at both ends with a conductor 111 from transformer coil 81. At the upper end it has connection with a conductor 72c, and at the lower end with a conductor 72b. The latter conductors are in the cable 72, previously mentioned, which also contains a conductor 72a extending from the opposite side of the 40 transformer coil 81.

Now, referring to the control for the direct radiation system, the valve 9 in steam pipe 20 comprises a butterfly valve piece 112, to which is attached a crank arm 113. The latter is connected by a link 114 with a crank arm 115 on an electric motor 116, or reduction gearing driven from said motor, the arrangement being such that when the crank arm 115 turns through half a revolution it swings arm 113 through an angle of 90°, and when the crank arm 115 turns through the second half of its revolution the crank arm 113 is swung back 90° to its original position. A valve operator of known form which may be employed for this purpose is illustrated 50 in Fig. 5, where the shaft for the butterfly valve is shown at 150. Rigidly secured thereto outside the valve casing is a crank 151 with a ball end 152. 153 and 154 are elements of a scissors clamp, which elements are urged toward their 60 closed position by a coil spring 155. The clamp elements 153 and 154 embrace the ball end 152 and also embrace a ball end 156 on one arm of a bell crank lever 157, the other arm of which is the crank arm 113. This lever is loosely 65 mounted upon the shaft 150, as are also the elements 153 and 154 of the scissors clamp. When the motor 116 turns the crank 115 through an angle of 90° the bell crank 113, 157 turns the scissors clamp through a like angle, and the 70 scissors clamp working through crank arm 151 turns the valve 112 until it comes into closed position against a stop 158. The motor crank 115 continues through another 90°, pushing against the element 154 of the scissors clamp. 75 The other element 153 of the clamp is kept from

turning by its engagement with the ball end 152, the movement of which is stopped with the movement of the valve. The scissors clamp therefore opens against the action of spring 155. Now, when the next operation of motor 115 occurs to cause the movement of crank 115 through another 180°, the first 90° of that movement swings the arm 113 back through an angle of 90°, this movement being assisted by the spring 155, which also permits scissors element 154 to swing 10 through the same angle, relieving spring 155 and returning the scissors elements to their closed position. The next 90° of the motor movement then works through the scissors to swing arm 151 and valve 112 back to the original position indicated in Fig. 5. The electric circuit 117, 118, for motor 116 includes a choke coil 119 which is adapted normally to prevent the flow of sufficient current to actuate motor 116. When, however, a circuit is completed through coil 120 wound upon 20 the same core with coil 119, current sufficient to operate the motor will flow through circuit 117, 118.

On the same shaft with crank 115 there is a switch arm 121, the outer end of which is 25 adapted to run upon a ring contact 122 having diametrically arranged arc-shaped protuberances within which are located contacts 123 and 124 which have no electrical connection with the ring. Coil 120 is connected through a conductor 125 with the hub of switch arm 121, and through a conductor 126 with the ring 122. Contacts 123 and 124 are connected through conductors 75a and 75b with contacts 127 and 128 of thermostat 74. The bimetallic arm of that thermostat is in electrical connection with conductor 126 through a conductor 129.

The position of the movable arm of thermostat 74 is dependent upon the temperature of that section of the premises heated by direct radiation. Assuming that the parts are in the position illustrated in Fig. 3, and that the temperature has risen to the point for which the thermostat was set, the movable arm of the thermostat will then engage contact 128, and a circuit will be 40 set up from coil 120 through conductors 126 and 129, thermostat arm 74, contact 128, conductor 75b, contact 124, switch arm 121 and conductor 125 back to coil 120. This flow of current relieves the choking effect of coil 119, and current then 45 flows through motor 116, turning the crank 115. Switch arm 121 turns at the same time, and moves away from contact 124. However it immediately makes contact with ring 122 which short-circuits thermostat 74 and provides a new path 50 for current through coil 120 by way of conductor 126a. Hence the circuit through the motor is maintained until the arm 121 moves off the ring 122 onto contact 123, whereupon the motor stops, having turned valve piece 112 through 90° into 60 the closed position.

Upon the same shaft with crank arm 115 and switch arm 121 there is another switch arm 130, the outer end of which is adapted to make connection with one or the other of two crescent 65 shaped contacts 131 and 132. Whenever the crank 115 moves through 180° the switch arm 130 leaves engagement with one of the contacts 131 or 132, and makes engagement with the other. Conductor 77a leads from contact 131 to binding 70 post 133 of solenoid 55, and conductor 77c leads from contact 132 to binding post 134 on the solenoid. Conductor 77b connects with conductor 72b, previously mentioned. There is a third binding post 135 on the solenoid to which con- 75

ductor 72a is connected, this conductor extending over to one end of transformer coil 81.

The upper end of rod 53 in solenoid 55 has a reduced portion which receives the notched ends 5 of two metal bars 136 and 137 that are loosely connected at their outer ends with flexible metal contacts 138 and 139, connected respectively to the binding posts 133 and 134. The binding post 135 is electrically connected with both of coils 10 56 and 57. Coil 56 is also connected with a contact 140 and coil 57 with a contact 141. When the valve 52 is closed and the bar 136 is in the position shown, coil 56 is in electrical connection with conductor 77a through contact 140, bar 136, 15 contact 138 and binding post 133. When the armature 54 moves upwardly, spreading the bars 136 and 137 in the manner of toggle links, the upper ends of contacts 138 and 139 flex backwardly or outwardly until the bars 136 and 137 20 are in alignment, and then impart a snap action to the same, forcing them upwardly, whereupon bar 137 engages contact 141 and coil 57 is brought into electrical connection with conductors 77c and 72c through contact 141, bar 137, spring 25 contact 139 and binding post 134.

The parts as illustrated in Fig. 3 are in the positions which would be assumed when the air system section 13 of the premises was heated to the extent called for by thermostat 71 and when 30 the section 18 of the premises was below the temperature required by thermostat 74. Steam is then flowing through radiators 19, valve 9 being open, and it is also flowing through radiator 59, but there is little condensation occurring in 35 the latter radiator because the circulation of air thereover is interrupted both by the closed condition of damper 15 and by the inactive condition of blower 62. If the casing of the warm air heater be well insulated the loss of heat 40 through radiation from radiator 59 will be very low indeed at such times.

Now, assume that the temperature of that section 13 of the premises wherein the thermostat 71 is situated drops below the degree of heat for 45 which the thermostat is set. The pointer 102 will then move along the rheostat 101, increasing the resistance through one of the coils 84 and 85 and decreasing it through the other. The contact 87 will then move toward the left and engage contact 88, whereupon heating coil 108 will 50 be energized and the pressure within bellows 91 will be increased, raising the lever 68. As soon as this action becomes sufficient to swing the lever 68 through a predetermined fraction of its 55 total possible movement, say one-sixth, the mercury globules 99 and 100 will travel to the opposite ends of mercury tubes 97 and 98. When this occurs the circuit through motor 66 by way of conductors 73a, 73b and 110 will be completed, 60 starting the blower 62. The raising of the lever 68 will at the same time have lifted link 67 and swung crank 17 to open damper 15 part way. Circulation of air over the radiator 59 and through the section 13 of the premises will then 65 take place. With the damper 15 in an intermediate position corresponding to any intermediate position of lever 68, the air handling capacity of blower 62 is reduced, and the condensing capacity of radiator 59 is correspondingly reduced 70 below the generating capacity of boiler 10, causing the steam pressure in the system to rise. Through pipe 42 this steam pressure is communicated to diaphragm 37 and thence to valve piece 34, reducing the flow of gas until the rate of heat 75 generation is just equal to the demand. The rate

of flow of the air in the air stream, which is dependent upon the action of the mechanism controlled by thermostat 71, therefore controls indirectly the degree of heat applied to the boiler 10.

At the same time globule 100 will function to connect conductors 111 and 72c leading to binding post 134 on solenoid 55. This will have no effect however, as the bar 137 is out of engagement with contact 141. Hence the solenoid 55 is not affected, which is as it should be because valve 52 is already in closed position, which corresponds to open position of the fuel valve 29.

Now, assume that after a length of time the temperature in that section of the premises wherein thermostat 74 is situated rises to the predetermined desired point, causing thermostat arm 14 to engage contact 128. A circuit is thereby made through coil 120 as heretofore explained, and the choking effect of coil 119 is relieved, permitting current to flow through motor 116 in amount sufficient to operate the same. As a result the crank arm 115 travels through an arc of 180°, valve piece 112 is shifted to the closed position, and switch arm 121 moves over onto contact 123, thereby breaking the circuit through coil 120 and stopping the motor 116. At the same time switch arm 130 is caused to leave crescent shaped contact 132 and to engage crescent shaped contact 131. This is the position of switch arm 130 for lifting valve 52, but it is ineffective because the circuit includes the contacts at the right-hand end of mercury tube 98, which are not joined because the globule 100 is at the left end of the tube. The valve 9 being closed however shuts off the flow of steam to radiators 19, whereby all of the steam generated in the boiler is then available for radiator 59.

As the temperature in the premises surrounding thermostat 71 rises toward the desired value, the thermostat pointer 102 gradually moves back to such position that the current through heating coils 84 and 85 changes in a manner such as to return yoke 86 to such position that lever 68 swings downwardly enough to cause globules 99 and 100 to travel again to the right-hand ends of tubes 97 and 98, whereupon the current through motor 66 is interrupted, stopping the blower 62, and conductors 111 and 72b are electrically joined. The damper 15 is also moved toward closed position by the lowering of lever 68 and link 67.

Both of the switches 98 and 130, 131 are now in position for opening valve 52 by the energization of coil 56. The circuit may be traced as follows: From coil 81 of the transformer through conductors 111, 72b and 77b to switch arm 130, which is then in engagement with contact 131, from the latter contact through conductor 77a to binding post 133, through spring contact 138, bar 136, contact 140, coil 56, binding post 135, and conductor 72a back to coil 81. Valve 52 consequently opens, enabling gas to flow into the chamber 49 of valve 29 and close that valve. The latter valve remains closed as long as both thermostats 71 and 74 remain satisfied.

If thermostat 74 should be the first one to call for heat, engagement would be made between the swinging arm of that thermostat and contact 127, which would complete a circuit through coil 120, the switch arm 121 being in the dotted line position at the time. The valve 9 would then be opened and the switch arm 130 would return to its full line position. Current would then flow from coil 81 through conductors 111, 72b, and 77b through switch arm 130, contact 132, con-

ductor 77c, binding post 134, spring contact 139, bar 137 (then in its upper position), contact 141, coil 57, binding post 135 and conductor 72a back to coil 81.

5 It will be observed that the circuit through coil 57 includes both of the switches 98 and 130, 132 in parallel, so that when either one of these switches is closed the coil 57 will be energized to effect the opening of the fuel valve. The coil 56
 10 however is in a circuit including switches 98 and 130, 131 in series, so that before this coil can be energized to effect the closing of the fuel valve, both of the said switches must be closed. There is, however, control of the heating medium for
 15 each system individually by means other than the fuel valve, that is to say, when thermostat 71 is satisfied switch 97 opens the circuit for motor 66 and lever 68 descends to close damper 15; while for the direct radiation system, when the
 20 thermostat 74 is satisfied valve 9 closes to shut off the flow of steam to the radiators 19. Hence there is a double control for each system, the fuel valve going to the on position when either one of the individual controls goes to the on position, and
 25 the fuel valve going to the off position only after both of the individual controls have gone to the off position. Furthermore the degree of opening of the fuel valve is controlled not only in proportion to the demand for heat in the direct radiation system, but also in proportion to the demand in the indirect system, that is to say, when the
 30 flow of air through the air conductor is slowed down on account of approach to the desired temperature level in the air heated part of the premises, then the steam pressure increases because of the lowered rate of condensation of steam in radiator 59. Consequently the gas intake valve is moved toward closed position, balancing the heat output to the demand. In other words,
 35 there is a coordination of air flow and the heat applied thereto which best fits any given condition of variance between desired temperature and
 40

actual temperature. The control therefore tends toward constant application of heat and air flow in controlled amounts rather than in intermittent application of either or both.

In the warm air system as herein disclosed there is both a blower and a damper for controlling the flow of air. It will be understood that either of these devices could be employed singly, with more or less satisfactory results, although the use of both, is deemed advisable. It will also
 10 be understood that the steam to radiator 59 could be turned on and off by means similar to that employed in connection with valve 9, but this is not considered necessary in view of the fact that the condensation of steam in radiator 59 when the air system is not in operation can be kept down to a
 15 low minimum.

In the foregoing description I have necessarily gone somewhat into detail in order to explain fully the particular embodiments of the invention herein illustrated, but I desire it to be understood that such detail disclosures are not to be construed as amounting to limitations, except as they may be included in the appended claim.

Having thus described my invention, I claim: 25

In apparatus of the class described, two separate heating systems, a common source of heat for said two systems comprising a fluid fuel burner, a fuel conductor leading to said burner, an electrically controlled valve in said fuel conductor, 30 an electric circuit adapted when energized to cause the opening of said valve, said circuit including two thermostatically controlled switches in parallel one for each system, whereby the closing of either of them will energize the circuit, and a second circuit adapted when energized to cause the closing of said valve, said second circuit including two thermostatically controlled switches in series, one for each system, whereby the circuit will be energized for closing the valve only when both switches are closed. 35 40

WILLET E. STARK.
